RUDOLPH VUILLEUMIER, OF NEW ROCHELLE, NEW YORK, ASSIGNOR TO THE SAFETY
CAR HEATING & LIGHTING COMPANY, A CORPORATION OF NEW JERSEY.

CUTTING-TORCH.

Specification of Letters Patent. Patented Aug. 22, 1916.

1,195,298.

Application filed December 12, 1913. Serial No. 806,162.

To all whom it may concern:

Be it known that I, RUDOLPH VUILLEUMIER, a citizen of the United States, residing in New Rochelle, county of Westchester, and State of New York, have invented a new and useful Improvement in Cutting-Torches, of which the following is a description.

This invention has reference to cutting torches, and particularly relates to torches adapted to utilize gases for the purpose of cutting metals.

Among the objects of my invention may be noted the following: to provide a torch with a tip adapted to utilize oxygen gas, in combination with some other gas or gases, as a means for cutting metals; to provide a gas torch, for cutting metals, having means for increasing its efficiency in operation by reducing the volume of gas necessary to be used in a given operation and, at the same time, increasing the speed of operation of the torch, thus decreasing the time for performing any given operation with the torch; to provide a cutting torch with a tip having a flame protector adapted to largely eliminate the entrainment of air; to provide a combination of means by which gases may be combined and properly distributed within the tip of the torch, so as to provide the effective flame, while another of the gases may be led independently to the point of flame production, so as to become effective in the use of the torch; to provide a cutting torch with means by which the flame may be materially shortened and intensified by automatically mixing the gases and confining the combustion thereof within a chamber, thus avoiding the diluent effect of inert nitrogen upon the other gases used; and to provide a torch-tip which is simple, compact, effective and economical in operation, and which may be economically produced.

With the above objects in view, and others which will be detailed during the course of this description, my invention consists in the parts, features, elements and combinations thereof hereinafter described and claimed.

In order that my invention may be clearly understood, I have provided drawings wherein:

Figure 1 is a sectional elevation of a torch-tip and so much of the associated parts as are deemed necessary to illustrate the application of my invention; Fig. 2 is a trans-

verse section substantially on the line 2—2 of Fig. 1, looking in the direction of the arrow adjacent said line; Fig. 3 is a transverse section substantially on the line 3—3 of Fig. 1, looking in the direction of the arrow adjacent said line; Fig. 4 is a section substantially on the line 4—4, Fig. 1, looking in the direction of the arrow adjacent said line; Fig. 5 is an enlarged view in sectional elevation, showing the executive end of the tip and substantially the mode of action of the gases; and Fig. 6 is a sectional elevation of the executive end of the tip, showing another form of construction contemplated by me.

Referring to the drawings, the numeral 1 indicates a union-nut, which couples the shank 2, of the torch-head 3, to the tube 4, containing a passage for mixed gases, this structure and the means by which the said gases are mixed being, in all material respects, substantially the same as set forth in my application filed September 29, 1913, Serial No. 792,287; and it should be understood that my present invention in tips for cutting torches contemplates the use of an admixture of oil-gas and air preliminarily combined in much the same manner as set forth in my said application. In my present invention, the torch-head is provided at its lower end with a reduced, screw-threaded portion 5, upon which is threaded the enlarged end 6, of the sheath 7 of the tip, the executive end of which sheath is tapered to the form of a hollow truncated cone, as indicated at 8. The upper end of the head 3 is extended into a reduced screw-threaded portion 9, receiving a coupling-nut 10, through the upper end of which is extended the pipe or tubing 11, the lower end of which is provided with an enlargement 12, adapted to set against the extension 9 of the head and be tightly coupled thereto by the nut 10. The pipe or tube 11 is for the introduction of oxygen-gas through the head and tip of the torch, its passage being extended through the upper end of the torch-head by means of the central bore 13, terminating in a large chamber 14, the upper end of which is screw-threaded internally to receive the screw-threaded upper end 15, of the tip, the body-portion of which, for considerable of its length below the screw-threaded portion 15, is provided with an exterior spiral-thread 17, operating as a gas-passage and mixing-chamber. The body-por-

tion of the tip, which is provided with the spiral-threads 17, has cut therein a plurality of longitudinal grooves 18, see Fig. 4, extending to the root of the spiral threads 17. Preferably, the grooves 18 are four in number and are equi-distantly spaced, and extend along the entire length of the spirally-threaded portion of the tip, thus extending from the screw-threaded portion 15, to the reduced portion 16, of the tip, between which latter and the sheath 7, the chamber 19 is formed, the latter thus being connected by the grooves with the gas-passage 20, through the shank 2, of the torch-head. Below the reduced portion 16, the tip is provided with an enlarged head 21, hexagonal in cross-section, as shown in Fig. 3, between the faces of which and the sheath 7, passages 22 are formed, the several angles 20 of the head impinging against the internal periphery of said sheath, thus making a contact between the tip and sheath, adapted to produce a rigid structure. Below the head 21 of the tip, the latter is tapered to truncated conical form, as at 23, correspondingly with the form of the lower end 8 of the sheath; but, the conical tip-end is only substantially half as long as the end 8 of the sheath, thus providing a combustion chamber 24, at the executive end of the tip, within the sheath. In producing the conical, executive end 23, of the tip, the surface of said end is rounded to conform to the inner surface of the sheath-end 8, and said tip-end 35 surface is provided with a plurality of V-shaped grooves 25, each extending longitudinally of said surface from the extreme lower end of said tip upwardly to the lower end of a flat face of the head, the form of said grooves 25 being such as to give to the extreme lower end of the tip 23 the six-pointed star shape shown in Fig. 2, the points of which star engage the inner periphery of the conical end of the sheath, thus producing, in the grooves 25, passages for the gas which communicate with the passages 22, which latter in turn communicate with the chamber 19. Extending entirely 45 through the length of the tip 16, is a central passage 26, the upper end of which communicates with the passage 13 in the head, and the lower end of which is reduced as at 27, and continues to the extreme lower end of 50 said tip, thus communicating with the chamber 24.

It will now be understood, from the above detailed description, that the gas mixture, flowing through the tube 4 and passage 20 of the shank 2, enters the chamber 14, of the head 3, and follows the circuitous path described by the spiral-threads 17, and also flows along the passages 18, of the body-portion of the tip until it enters the chamber 19, between the reduced portion 16 and sheath 7, the gases having, in the mean-

time, become most effectively mixed and commingled, the said circuitous path of travel of the gases resulting in imparting to the latter a whirling action, which is exceedingly effective as a mixer of the gases. Passing through the chamber 19, the gases flow through the passages 22, around the head 21, and thence through the groove-passages 25, to the chamber 24. In addition, the oxygen, or other cutting gas, supplied through the pipe 11, flows through 75 passages 13, 26 and 27, to the chamber 24. Under working conditions, the heating-flame assumes a substantially conical form, and takes its origin at the lower conical end 23, 80 of the tip inside the chamber 24, the flame propagation being in an outward direction, as clearly represented in Fig. 5, and is duplex in character. That is to say, in the operation of the torch, the admixture of 85 gases passing between the tip and the sheath, and flowing to the chamber 24, has a tendency, in its egress from the tortuous passage between the tip and sheath, to hug the inner wall of the sheath and form into a 90 hollow-flame cylinder *a*; but, combustion of the gases taking place in the chamber 24, close to the end 23 of the tip, results in the production of a second flame-cylinder *b*, within the other, as clearly shown in Fig. 5. The 95 ejection of the flame bodies thus formed takes place with considerable velocity, so that the central flame-cylinder *b* entrains the flame-cylinder *a*, which latter has a tendency to hug the walls of the chamber 24, resulting 100 in the two flame-cylinders combining a short distance beyond the executive end of the tip, or extreme end of the sheath into an intense flame, substantially as indicated by *c*.

The structural features described and the 105 functional coöperation thereof result in a cutting-torch productive of a short and intense cutting-flame, which is characterized by the maintenance of combustion inside of a chamber of comparatively small diameter. 110 Moreover, the executive end of the tip, including the sheath and head, do not become unduly heated for the reason that the head and sheath are at all times in contact with gases of comparatively low temperature, 115 while externally the sheath is surrounded by comparatively cool air.

I have, in the foregoing description, described my invention, in some particulars, with reference to oil-gas, as described in my 120 aforesaid application; but, it will be obvious to those skilled in the art that my torch can be employed in connection with gases of other kinds, having greater or less heat-producing units. In fact, it is one of the 125 important features of my invention that it contains means for utilizing a gas which is poor in heat units; and, in practice, my torch has been found capable of reducing the time of a given operation approximately 130

50% and also reducing the amount of gases used approximately 50%.

In the form of my invention shown in Fig. 6, I have provided an extended tube or inner tip 28, which is formed in any suitable manner on the extreme lower end of the executive end of the tip 16, and through which the passage 27 is continued. By this means, the oxygen gas is conducted through the 10 combustion-chamber 24, and may or may not combine with the gases in said chamber, according to the length of said tip 28, it being understood that said tip may be carried to the extreme lower end of the sheath, or may 15 terminate at a predetermined distance short of said end.

Having thus described my invention, what I claim and desire to secure by Letters Patent is:

- 20 1. A cutting-torch comprising a head having a tip secured thereto, said head having a chamber and a plurality of passages leading thereto for the admission of different gases, the tip being provided with a circumferential circuitous passage communicating with one of said passages, and with an independent passage formed in continuity with another of said passages.
- 25 2. A tip for cutting-torches comprising a body-portion, a sheath encircling the same, means between the two providing a circuitous passage for gas, and the body-portion having an independent passage for gas, said body-portion, at its lower end, terminating 35 a short distance within the terminal end of the sheath, whereby a combustion-chamber is provided at the executive end of the tip.
- 30 3. A tip for cutting-torches comprising a body-portion, a sheath surrounding the same, the body-portion being provided with a central, longitudinal passage and with a circumferential, spiral passage, the executive end of the tip being provided with a chamber with which both said passages communicate.
- 40 4. A tip for cutting-torches having a central gas-passage, and a spiral passage surrounding the central passage, and also having a plurality of longitudinal passages intersecting the spiral passage, said tip having 45 at its executive end a combustion-chamber.
- 45 5. A cutting-torch comprising a head having a shank extending therefrom, said head having a chamber therein and a passage leading to said chamber and said shank having a passage communicating with said

chamber; a tip removably secured to the head within said chamber and having a plurality of passages communicating with the passage through the shank, said tip also having a central passage formed in continuity with the passage extending through the head; and independent means for supplying gas to the head-passage and to the shank-passage. 65

6. A tip for cutting-torches comprising an inner and an outer member, means providing straight gas-passages through and between the inner member and the outer member, and a circuitous passage between said members and the executive end of the inner and outer members having a conical form and forming between them, at the extreme lower end, a chamber into which the several gas-passages discharge. 75

7. A tip for cutting-torches provided with a plurality of longitudinal passages for gas, said tip also having a spiral passage intersecting the other passages; and said tip having at its executive end a chamber with 80 which all the passages communicate, said executive end of the tip having a conical form so as to tend to concentrate the gases at a given point.

8. A cutting torch comprising a head having a chamber and passages leading thereto, a tip removably secured to said head and provided with a combustion-chamber at its executive end, said tip being also provided with a plurality of independent gas-passages 90 communicating with said chamber and entering the said combustion-chamber, whereby different gases may be conducted to the combustion-chamber without being previously combined or intermixed. 95

9. A cutting torch comprising a head having a chamber and passages leading thereto, a tip set in the chamber of said head and provided with a combustion-chamber at its executive end, said tip being provided with 100 a plurality of gas-passages independent of each other, and one or more of said passages entering said combustion-chamber and head chamber.

In testimony whereof I have hereunto 105 signed my name in the presence of two subscribing witnesses.

RUDOLPH VUILLEUMIER.
